KEG

Charles Lipson, Atlantic City, N. J., assignor to
Charles Lipson Company, Atlantic City, N. J.

Application April 16, 1952, Serial No. 19,351

Term of patent 3½ years

(Cl. D58—3)

To all whom it may concern:

Be it known that I, Charles Lipson, a citizen of the United States of America, residing at Atlantic City, in the county of Atlantic, and State of New Jersey, have invented a new, original, and ornamental Design for a Keg, of which the following is a specification, reference being had to the accompanying drawing, forming a part thereof.

In the drawing:

Figure 1 is a plan view of a keg, showing my new design,

Figure 2 is a side elevational view of the same.

Figure 3 is a fragmentary sectional view taken on the line 3—3 of Figure 2.

I claim:

The ornamental design for a keg, as shown.
CHARLES LIPSON.
